The ornamental design for a control box for a pressure activated alarm system, as shown and described.

DESCRIPTION

FIG. 1 is a perspective view of a control box for a pressure activated alarm system.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top view thereof; and,

FIG. 7 is a bottom view thereof.

The broken lines in the figures are included for the purpose of illustrating environment and form no part of the claimed design.
